UNITED STATES PATENT OFFICE.

WILLIAM D. BERRY, OF NEW BRIGHTON, PENNSYLVANIA.

APPARATUS FOR MAKING TUBULAR SAND CORES.

No. 887,757.

Specification of Letters Patent.

Patented May 19, 1908.

Application filed June 12, 1907. Serial No. 378,633.

To all whom it may concern:

Be it known that I, WILLIAM D. BERRY, a resident of New Brighton, in the county of Beaver and State of Pennsylvania, have invented a new and useful Improvement in Apparatus for Making Tubular Sand Cores; and I do hereby declare the following to be a full, clear, and exact description thereof.

This invention relates to apparatus for making sand cores and more especially for making ring-like or shell cores for use in casting cored-out tubular articles, such as twyers, coolers, cinder notches and the like.

The object of the invention is to provide apparatus for making this character of cores which is adapted for machine jarring so as to dispense with hand labor which is ordinarily employed for this purpose and to greatly expedite the making of such cores as well as getting a more uniform product.

The invention comprises the construction and arrangement of parts hereinafter described and claimed.

In the accompanying drawings Figure 1 is a vertical sectional view through the apparatus showing a portion of the jarring machine; Fig. 2 is a vertical section showing a portion of the molding parts; Fig. 3 is a plan view of the shell core plate; Fig. 4 is a bottom view of a portion thereof; Fig. 5 is a sectional view of one of the bushings employed; and Fig. 6 is a plan view of one of the wire rings used.

Any suitable jarring mechanism may be used in conjunction with my improved apparatus. In Fig. 1 a portion of a jarring machine is shown, this comprising the frame 1 on which the machine plate 2 is mounted for vertical movement. This plate may be actuated by any suitable mechanism, the drawings showing a power cylinder 3 for lifting the same and permitting it to drop upon an anvil 4.

In using my apparatus I place upon the machine plate a suitable mandrel plate 6 preferably provided with a central opening 7 for receiving a threaded stud 8 to be used in securing the central pattern or mandrel 9 to the plate, by inserting in the mandrel a threaded bushing 10 which may be secured to the mandrel by any suitable means, such as screws 11. This mandrel will, of course, be made of a shape to conform to the interior of the ring or shell core. Also resting on the mold bottom plate 6 and fitting around the lower portion of the mandrel 9 is

a shell core ring 12, or "shell core plate" as it is called, upon which the core box 13 is arranged to rest, the shell core plate being provided with an annular shoulder 14 over which a downwardly projecting lip 15 on the core box projects in order to hold the core box centered. The core box is made of a form to suit the exterior of the ring or shell core, the latter being formed in the annular space between the mandrel and the core box.

The shell core plate 12 is provided with the holes 16 for receiving the lower ends of anchoring members 17 which are embedded in the core, and in order to adapt said core plate to the making of cores of various sizes it is provided with a plurality of series of holes 16, the drawing showing five sets of holes of four each, each set being spaced a different distance from the center than the others. As shown, there are four holes in each set, thus giving four anchoring members 17 per core. Only one set of holes is used at a time and the others are closed so as to avoid filling with sand. Any suitable closure may be used for this purpose, the drawings showing a disk 18 to which is connected a U shaped spring 19 extending down into the hole and having its ends entering depressions or slots 20 cut in the lower face of the plate so as to prevent the disk from getting out of place, but leaving it easily movable.

The anchoring members 17 are also preferably used as vents to permit the escape of gases while casting and are therefore formed of tubes provided with perforations 21 and are adapted to have their upper ends closed by any suitable means, such as the disks 22. These anchors not only serve to center the core in the mold and to secure the core to the base plate of the flask when casting so as to prevent the core from rising due to the weight of the molten metal being poured in, but also serve as supports for the core and hold it in proper position in the mold cavity, as well as providing means for adjusting the position of the core vertically in the mold. The particular core shown is for use in casting cored out water cooled twyers, the anchors passing out at the points where the holes are made through the wall of the larger end of the twyer.

The core remains on the core plate 12 until the core is baked and strong enough to be handled, and since the sand expands in the process of baking provision must be made to relieve that portion of the sand, shown at 23,

which extends down into the holes 16 in the core plate. This is done by providing bushings 24 which fit loosely in the holes in the core plate and which are removed before 5 baking, thus leaving space for the expansion of the sand. The slots 20 in the lower face of the core plate serve not only as an anchorage for the ends of the springs 19 but also give opportunity to grasp the lower ends 10 of the bushings 24 to remove the same. The openings in the bushings 24 are flaring, as shown, so as to form the part 23 of the core tapering, which provides for adjustment of the core vertically in the mold, said conical 15 parts 23 pressing down into the sand of the drag. This also gives a tight joint at this part of the mold.

In case an inwardly projecting flange is to be formed around a hole a removable collar 20 25 is placed on the core plate 12 and around the upper end of the bushing 24. The anchor members 17 at their lower ends will be provided with suitable means for securing the same to the bottom plate of the flask, 25 the drawings showing for this purpose internally threaded sockets 26 secured to the threaded lower ends of the anchors and adapted to receive nipples or other securing means. The anchors 17 and sockets 26 do 30 not, however, extend below the bottom face of the core plate 12, so that the molded core can be carried by means of said ring and supported thereon in the oven while baking.

To assist in strengthening the shell like 35 core and prevent the sand from breaking before baking, I provide one or more horizontal strengthening members 30 so constructed as to adjust its diameter with the sand in descending over the conically arranged anchor- 40 ing members, and not spring back when taken from the mandrel. Ordinary rings have been used for this purpose but under the load of sand being packed down into the mold these rings were forced to slide down 45 on the tapering anchors, thus partially straightening the portion of the rings between the anchors. The consequence is that the metal of the ring is put under tension and when the core is taken from the 50 mandrel they tend to resume their normal circular shape with the result of fracturing the sand. To avoid this I make the rings 30 expansible, such as over-lapping the ends of the rings for a considerable distance and 55 providing the ends with eyes 31 surrounding the ring proper so that under pressure the rings can expand, the eyes merely sliding over the wire as will be readily understood. The consequence is that the rings merely ex- 60 pand when sliding down instead of being put under strain.

In conjunction with the apparatus I use an ordinary reservoir 33 and a center cone 34 placed on top of the core box and man- 65 drel respectively. If desired, the mandrel

plate 6 may be dispensed with and the machine plate used for this purpose.

In the use of the apparatus the mandrel 9 is first secured to the mandrel plate 6 after which the core plate 12 is placed around the 70 mandrel and the anchor members 17 with bushings 24 surrounding their lower ends inserted in four of the holes 16 of the core plate, the remaining holes being closed by the disks 18. The tops of the tubular anchors 17 are 75 closed by the disks 22 and the core box is then set upon the core plate 12 after which the whole is brought underneath the reservoir and sand is fed down in the usual way. The machine is then put in operation, thus 80 jarring the sand down into the space between the mandrel and core box and also down into the flaring upward ends of the bushings 24. When the jarring is completed the sand is cut off at the top of the 85 core box, the core box removed and the core raised by means of the core plate 12, thereby stripping the core from the mandrel. The bushings 24 are then removed and the core baked.

Various changes can be made in the devices described without departing from the spirit of my invention or the terms of the claims herein made.

What I claim is:

1. Core molding apparatus comprising a mandrel plate provided with mandrel securing means, an annular shell core plate or ring seating on said mandrel plate and surrounding the base of the mandrel and a core box 100 seating on said core plate.

2. Core molding apparatus comprising a mandrel plate provided with a threaded boss for securing the mandrel, an annular shell core plate or ring resting on the mandrel 105 plate and surrounding the base of the mandrel and provided with anchor receiving openings, and a core box seating on the core plate.

3. Core molding apparatus comprising a mandrel plate, a shell core plate resting on 110 said mandrel plate and provided with a plurality of sets of anchor receiving openings, each set being a different distance from the center than the other sets, closures for said openings, and a core box seating on said core 115 plate.

4. Core molding apparatus comprising a mandrel plate, an annular shell core plate resting on the mandrel plate and surrounding the base of the mandrel and provided 120 with anchor receiving openings, and a core box seating on said core plate.

5. Core molding apparatus, comprising a core plate provided with a plurality of sets of anchor receiving openings, each set being 125 a different distance from the center than the other sets, closures for said openings, and a core box seating on said core plate.

6. Core molding apparatus comprising a core plate provided with a plurality of sets 130

- of anchor receiving openings, closure disks for said openings provided with springs projecting down into the openings and engaging the same frictionally, and a core box seating 5 on said plate.
7. Core molding apparatus comprising a core plate provided with anchor receiving openings, removable bushings in said openings fitting the lower ends of the anchors, and a core box seated on said core plate.
- 10 8. Core molding apparatus comprising a core plate provided with openings, bushings in said openings for receiving the lower ends of anchoring members and flaring upwardly, 15 and a core box seating on said core plate.
9. Core molding apparatus comprising a core plate provided with anchor receiving openings, removable bushings fitting in said openings and flaring upwardly, a removable 20 collar or ring seated on the core plate and surrounding the upper end of a bushing, and a core box seating on said core plate.
10. Core molding apparatus comprising a core plate provided with anchor receiving 25 openings, anchor members projecting into said openings but not extending below the lower face of the plate and provided on their lower ends with threaded members, and a core box seating on said core plate.
- 30 11. Core molding apparatus comprising a core plate provided with anchor receiving openings, anchors projecting down into said openings, but not extending below the lower
- face of the plate threaded sockets on the lower ends of said anchors, and a core box 35 seating on said core plate.
12. Core molding apparatus comprising a core plate provided with anchor receiving openings, perforated pipes projecting into said openings and provided with anchoring 40 members at their lower ends, and closures for the tops of said pipes.
13. Core molding apparatus comprising a core plate provided with openings, perforated pipes provided with threaded sockets 45 at their ends and projecting into said openings, removable bushings in said openings, and closures for the upper ends of the pipes.
14. Core molding apparatus comprising a core plate provided with anchor receiving 50 openings, anchors projecting down into said openings, and expansible rings surrounding said anchors.
15. Core molding apparatus comprising a core plate provided with anchor receiving 55 openings, anchors projecting down into said openings, and rings surrounding said anchors, said rings having overlapping ends and provided on their ends with eyes surrounding the ring proper.
- 60 In testimony whereof, I the said WILLIAM D. BERRY have hereunto set my hand.
- WILLIAM D. BERRY.
